UNITED STATES PATENT OFFICE.

FERDINAND HUMMEL, SR., AND WILLIAM HUMMEL, OF PADUCAH, KY.

NOZZLE FOR OIL-CANS.

SPECIFICATION forming part of Letters Patent No. 277,287, dated May 8, 1883.

Application filed March 20, 1883. (Model.)

To all whom it may concern:

Be it known that we, FERDINAND HUMMEL, Sr., and WILLIAM HUMMEL, of Paducah, in the county of McCracken and State of Kentucky, have invented certain new and useful Improvements in Nozzles for Oil-Cans; and we do hereby declare the following to be a full, clear, and exact description of the invention, such as will enable others skilled in the art to 10 which it pertains to make and use it, reference being had to the accompanying drawings, which form part of this specification.

Our invention relates to an improvement in nozzles for oil-cans; and it consists in the combination of a can cover or top, provided with an opening through which the can is filled, and a discharge-nozzle, each one of which openings has a rim or flange formed around its inner edge or end, and a rotating cut-off, as will be 20 more fully described hereinafter.

The object of our invention is to produce a cheap and simple nozzle for cans, in which both the nozzle and the opening through which the can is filled are opened and closed at the same time.

Figure 1 is a vertical section of our invention, taken through the two openings. Fig. 2 is an inverted view of the same, showing the cut-off turned so as leave both of the openings in the 30 cover open.

A represents the top of the cover, and B the flange which is connected thereto. This part A will be made of thicker and heavier material than the flange, as no strength, comparatively speaking, is needed in the flange. Through the part A are made three openings, the one C being the opening through which the can can be filled, and the one D being the nozzle or discharge pipe. The central 40 opening, E, is made directly through the center, and through it is passed the stem of the handle F. To the lower end of the stem is secured the cut-off G, which may either be of the form here shown or any other that may 45 be preferred, and which can be turned through a quarter of a circle, more or less, so as to open and close the two openings C D at the will of the operator. In order to form a tight joint between the cut-off and the lower ends

of the openings C D, there is a rim or flange, 50 H, formed around the lower end of each of the openings, and this rim or flange will preferably be formed of solder or some other material. When the cut-off is turned so as to close these two openings, it forms an air-tight 55 joint with these two flanges, and thus prevents all leakage in case the can is upset, and all evaporation in case the can is left standing for any length of time. In order to keep this cut-off pressed tightly against the 60 under side of the cover, the end of the stem projects a suitable distance below the cut-off, and bearing against the end of this stem is a suitable spring, I. The pressure of this spring forces the cut-off upward, and yet allows it 65 to yield and move downward slightly at the ends when the cut-off is being turned, so as to move over the two openings C D. In order to add still greater pressure for the purpose of holding the cut-off against the under side 70 of the top, a second spring, J, is placed upon the cover, and has the stem of the handle to pass down through it. Between the handle and the spring is a suitable washer, O, which serves to prevent any lateral pressure upon 75 the stem of the handle, and thus keep it always in a vertical position. These two springs may be used together, or either one may be used alone, as may be thought best. For the purpose of limiting the distance the cut-off 80 shall be turned, there is secured to the under side of the top a suitable stop, P, against which one end of the cut-off strikes when the cut-off is in position to close both holes, and against which the other end strikes when the 85 cut-off is turned so as to open both holes. When the cut-off is turned so as to open both holes the oil or other fluid will then flow freely through the discharge-nozzle, and the other hole will then serve as a vent for the can. 90

Having thus described our invention, we claim—

1. The combination of a can cover or top provided with the two openings C D, the rims or flanges which are formed on the lower ends 95 of these openings, and a rotating cut-off, substantially as described.

2. The combination of a can top or cover

provided with suitable openings, the flanges which are formed around the lower ends of these openings, a rotating cut-off, a suitable spring or springs for pressing the cut-off against the under side of the cover, and a stop for limiting the movement of the cut-off, substantially as specified.

In testimony whereof we affix our signatures in presence of two witnesses.

FERDINAND HUMMEL, SR.
WILLIAM HUMMEL.
